UNITED STATES PATENT OFFICE.

GEORGE W. MINTZER, OF PHILADELPHIA, ASSIGNOR TO HOWARD M. CLARK,
OF TIDIOUTE, PENNSYLVANIA.

CASE FOR HOLDING PLAYING-CARDS.

SPECIFICATION forming part of Letters Patent No. 389,093, dated September 4, 1888.

Application filed April 24, 1888. Serial No. 271,707. (No mo^{el.})

To all whom it may concern:

Be it known that I, GEORGE W. MINTZER, a citizen of the United States, and a resident of the city and county of Philadelphia, and 5 State of Pennsylvania, have invented certain new and useful Improvements in Cases for Holding Cards and other Like Articles, more particularly Playing-Cards, of which the following is a specification.

10 The object of the invention is to furnish an ornamental, convenient, and inexpensive case for holding and carrying cards and similar articles, and to provide for the easy and quick removal or insertion of the cards when desired without any danger of injury to the cards, and in which the cards are partially retained in the case by the pressure of the covers when closed, the inner face of the covers being preferably lined or provided with a suitable 15 soft or yielding facing.

20 The novelty resides in the peculiarities of construction and in the new combinations, construction, and arrangement and adaptation of parts, all as more fully hereinafter described, 25 shown in the drawings, and then particularly defined by the appended claims.

The invention is clearly illustrated in the accompanying drawings, which, with the letters of reference marked thereon, form a part 30 of this specification, and in which—

Figure 1 is a plan of my card-case when opened and the cards removed. Fig. 2 is an end elevation of the same with the cards shown in dotted lines and broken off. Fig. 3 is an 35 end elevation of the case when closed with the cards therein, and Fig. 4 is a perspective view of the case when closed and filled with cards.

Referring to the details of the drawings by letter, A designates one of the covers, and A' 40 the other, the two being connected by the back B, in any well-known manner, these parts being similar to the covers and back of an ordinary book or album, and have the same general appearance. They may be made of any 45 desired material, and as ornamental as the taste of the manufacturer may dictate.

Upon the back of the case, and secured thereto in any well-known way, preferably by means of rivets or screws a, is a spring, C, as 50 shown in Figs. 1 and 2. This clasp or spring

is made of suitable resilient material, and the arms thereof are turned slightly outward at their free ends, as seen in Fig. 2, leaving a rounded contacting surface for the cards as they are placed between said arms, so as not 55 to injure the said cards.

The edges of the covers are preferably bound with strips b of metal, as shown in the drawings, both for strength and appearance, and are preferably furnished with a clasp, c, and a 60 catch, d, by means of which they may be secured when closed; but it will of course be understood that other means of fastening the covers in their closed position may be employed without departing from the spirit of 55 my invention.

The inner faces of the covers are preferably lined or faced with some soft yielding material, as shown at e, so that when the case is closed this material may inclose the cards, and, 70 together with the spring C, prevent them from falling from their place, and, being yielding, the said facing gives to the pressure of the ends of the arms of the spring and permits of the case closing tighter than would be the case 75 were the covers made of an unyielding material and without injury to the inside of the covers.

When the cards are in place and the covers closed, the whole presents the appearance of 80 a small book or album, which may be carried in the pocket without danger of the cards falling from place or becoming soiled or torn, and which, when placed upon a table, presents a 85 very handsome appearance.

The outwardly-turned ends of the arms are an important feature, for it provides for the insertion of the cards between the said arms from the top without any danger of scratching the said cards, and they can also be inserted 90 much easier and quicker than they could be if they had to be pushed or slid in from the end lengthwise of the back B.

I deem it important that the arms of the spring extend parallel with each other from 95 their junction with the back of the spring to the rounded portion near their ends, for by this construction I provide a long bearing on the cards without injury thereto, there being no bearing at the ends, and, the said ends be- 100

ing turned outward and rounded at the place where the turn occurs, the cards cannot be marred at that place.

Having thus described my invention, what I claim as new is—

1. The combination, with the case consisting of the back and the covers flexibly connected thereto, of the spring C, substantially U-shaped, with its arms extended at right angles to the back, and the ends of said arms turned outward, leaving a rounded portion, said arms being parallel with each other from their junction with the back of the spring to

said rounded portion, as shown, and for the purpose specified.

2. The case described, consisting of the back and the covers flexibly connected thereto, the spring secured to the inner face of said back, and a yielding facing secured to said covers on the inner side thereof, substantially as and for the purpose specified.

GEO. W. MINTZER.
